UNITED STATES PATENT OFFICE.

CHARLES D. NEELY, OF CHICAGO, ILLINOIS.

DANCING-CLOG.

1,138,684.

Specification of Letters Patent. Patented May 11, 1915.

Application filed October 7, 1914. Serial No. 865,498.

To all whom it may concern:

Be it known that I, CHARLES D. NEELY, a citizen of the United States, residing at Chicago, in the county of Cook and State of Illinois, have invented certain new and useful Improvements in Dancing-Clogs, of which the following is a specification.

This invention relates to that class of shoes known as "dancing clogs," the same being characterized by a sounding device mounted in the heel of the shoe and actuated by the movement of the foot in stamping or dancing.

The invention has special reference to the sounding device, and its object is to provide a novel and improved structure which will not mar the floor, and which emits a sound on each stroke. This object is attained by means of a combination and arrangement of parts to be hereinafter described and claimed, reference being had to the accompanying drawing, in which—

Figure 1 is a plan view showing the application of the invention, and Fig. 2 is a side elevation, partly in section, on the line 2—2 of Fig. 1.

Referring specifically to the drawing, 5 denotes the heel of the shoe, in the bottom of which is a recess 6 to receive the sounding device. This device is a metal plate 7 having on its inner side a recess 8 which is closed by a metallic cover plate 9 secured by screws 10 which are countersunk in the outer face of the plate so as to leave the same smooth and devoid of projecting parts liable to scratch or mar the floor. The screws also serve to secure the device in the recess of the heel. In the center of the plate is an opening 11 and in the recess is loosely mounted 30 a sounding member comprising a disk 13 having on one side a stud 14 which projects loosely through the opening 11. The depth of the recess is greater than the thickness of the disk, thus leaving the latter free to be 35 jarred up and down in the recess, and the length of the stud is such that when the disk is at rest on the bottom of the recess, said stud projects through the opening a short distance below the outer face of the 40 plate 7. Thus, when the wearer moves the foot in stamping or dancing, the disk is jarred up and down between the cover plate 9 and the bottom wall of the recess 8, and is sounded upon striking each of these parts.

The outer end of the stud 14 has its edge 55 rounded off, which, together with the small size of the stud, prevents the latter from catching on the floor and marring the same. The stud can also pass easily over obstructions or rough places and will not get stuck. 60

I claim:

1. A sounding member for dancing clogs comprising a plate having a recess in one side provided with an upper wall, and an opening from said recess through the other side, and a sounding device loose in the recess, said sounding device being a disk adapted to come in contact with opposite walls of the recess to produce a sound, the thickness of the disk being less than the depth of the recess, and said disk having a stud projecting through the opening in the plate and below the same when the disk engages the bottom wall of the recess. 70

2. A sounding member for dancing clogs 75 comprising a plate having a recess in one side, and an opening from said recess through the other side, a cover plate closing the recess, and a sounding device in the recess, said sounding device comprising a disk 80 which is free to move between the cover plate and the bottom wall of the recess, and to come in contact with said parts to produce a sound, said disk having a stud projecting through the aforesaid opening in the 85 first-mentioned plate and below the same when the disk engages the bottom wall of the recess.

3. A sounding member for dancing clogs comprising a plate having a recess in one 90 side provided with an upper wall, and an opening from said recess through the other side, and a sounding device loose in the recess, said sounding device being a disk, the thickness of which is less than the depth of 95 the recess, and which disk is adapted to come in contact with opposite walls of the recess to produce a sound, said disk having a stud projecting through the opening in the plate and below the same when the disk 100 engages the bottom wall of the recess, the outer end of the stud having a rounded edge.

In testimony whereof I affix my signature in presence of two witnesses.

CHARLES D. NEELY.
